UNITED STATES PATENT OFFICE.

AUGUST VOELKER, OF BEUEL, NEAR BONN, GERMANY.

ELECTRIC-RESISTANCE MELTING-FURNACE.

1,051,036.

Specification of Letters Patent. Patented Jan. 21, 1913.

Application filed February 18, 1911. Serial No. 609,468.

To all whom it may concern:

Be it known that I, AUGUST VOELKER, a subject of the King of Prussia, German Emperor, residing at 77^a Siegburgerstrasse, Beuel, near Bonn, in the Empire of Germany, have invented a new and useful Electric-Resistance Melting-Furnace, of which the following is a specification.

Quartz melting furnaces are known, consisting of a carbon core in the shape of a rod, which is inclosed on the central part of its length by a concentrically arranged tubular shell, leaving an annular space around said core, and which will in consequence of an electric current sent through it, fuse the arenaceous quartz filling out said annular space progressively from the inside to the outside. The drawbacks of these melting furnaces consist in it being possible, indeed, to make the outer portions of the quartz body produced in the annular space, cohere, and even to create on it a thin glaze-like fused film of the shell generally made of carbon surrounding the central heating core; it is, however, not possible to so thoroughly fuse the interior of the quartz charge so that a product is obtained of a uniform structure throughout, although it is of the greatest importance for the subsequent treatment of the quartz body and the quality of the articles made therefrom.

My invention relates to improvements in such electric furnaces, whereby the said drawbacks are avoided.

One improvement consists in connecting the outer shell at one end by means of a conductor in series with the inner core passing through the shell.

Another improvement consists in longitudinally adjustable connections on both the shell and the core for the conductor between the shell and the core at the said one end and for the current cables at the other end.

A third improvement consists in the longitudinal adjustment of the core relatively to the shell. Then the electric current will first longitudinally pass through the shell and then by means of the conductor through the core. Thereby it is obtained, that, although at first, that is at the commencement of the working of the furnace, the outside shell will be heated, even if not up to the melting temperature of the quartz, and with it the adjoining portion of the quartz charge,—the current will, according to the duration of the passage of the cur-

rent and the progress of the fusion, gradually pass, besides in a longitudinal, also in a radial direction from the shell to the core through the charge becoming conductive in consequence of the fusion, so that a final product of homogeneous structure is obtained. This process may be regulated by gradually shifting the points of connection on the shell and the core as thereby the resistances and also the heating effect may be varied.

It is true, electric melting furnaces are known, in which a crucible-like melting chamber, closed below, is employed as series resistance for a centrally arranged live heating core in contact with the bottom. But with such arrangement it is intended to keep the walls of the crucible cold and save the latter, by increasing the heating of the core; these arrangements further lack the feature of the core transsecting the crucible at both ends and of the displaceable connections controlling the intensity of the current. They are therefore more or less unsuited for the purpose of a uniform fusion of the quartz charge intended by the present invention.

In the accompanying drawing a constructional form of the invention forming the subject matter of the present application is exemplified. It must be understood, that the invention shall not be limited to this one constructional form only.

It consists of a furnace body *a* supported on trunnions turning on stands *b*, and is lined with insulating material. Into said body *a* is fitted a carbon tube *c* in such a manner that it projects at both ends from the furnace. The ends of the tube *c* are closed by suitable disks (not shown) of insulating material and provided with a central hole. Where so preferred, of course these disks may be set off on the periphery, in other words they may be provided with shoulders adapted to bear against the annular end faces of the tube *c*, so that they may be inserted and detached easily. Through the central holes of these two disks a comparatively thin carbon or graphite rod *d* is passed and the space between said rod, the inside of the shell *c* and said two disks is filled with arenaceous or other raw quartz. The two ends of the carbon bodies *d* and *c* carry displaceable contact rings *f¹*, *f²* and *e¹*, *e²* respectively made of the same material. Terminals *g¹*, *i¹* are provided on the contact

rings e^1, f^1 at the lower end for introducing the current to and letting it out from the shell tube c or the heating core d respectively, while similar terminals g^2, i^2 are provided on the contact rings e^2, f^2 at the upper end and a bar h is provided for connecting the terminals g^2, i^2 at various heights by means of a series of holes and for serving as a conductor, it conducting the current from 10 e^1 to d .

While the furnace is working the current enters at e^1 into the shell c , flows through the latter and the bridge bar h into the core d and from the core d into the conductor connected to the terminal i^1 . At first, as long as the raw charge between c and d has not yet melted, the higher temperature of core d will fuse the surrounding layers of the charge, while the quartz along the inside 15 shell c will cohere and cake. With the progressing fusing of the charge the same will become conductive, in consequence of which the current will no more flow through the bodies c and d in a longitudinal direction 20 only, but will also pass in a radial direction through the charge, purify it and fuse it in a homogeneous manner. The resistance of the carbon bodies c, d varying with the duration of the passage of the current and the 25 progressing fusion, may be compensated or also an intentional variation of these resistances may, for the purpose of obtaining a more rapid fusion and purification of certain parts of the quartz charge, be produced 30 by changing the position of the admission and outlet terminals i^1, i^2 and g^1, g^2 respectively by displacing the contact rings f^1, f^2 and e^1, e^2 on their respective carbon bodies d and c , so that the length of the path 35 of the current and the heating effect on the parts of the charge penetrated may be easily 40 regulated.

I claim:

1. An electric melting furnace, in which a 45 thin live resistance heating core is concentrically surrounded at a given distance by a tubular shell forming a space for the charge between the core and the shell, the said tubular shell connected by a conductor as a 50 series resistance in series with the heating core, whereby the current entering at one end of said shell will flow longitudinally through the same, then pass into said conductor connecting the shell with the core and finally come out at the other end of the core 55

into an accessible conductor, the contact means for the connections of the current being displaceable.

2. An electric melting furnace consisting of a furnace body lined with insulating material, a carbon tube in said body projecting at both ends, two removable covers of insulating material provided with central holes at both ends of said tube, a thin carbon rod guided in the holes of said two covers and 60 projecting therefrom at both ends, whereby an annular space for the charge is formed between said rod, the inside of said tube and said two covers, a contact ring adjustable on the tube at one end and connected with an inlet terminal, a similar contact ring adjustable on the tube at the other end and conductively connected with a bridge bar provided with holes, an adjustable contact ring on the corresponding end of the carbon rod and conductively connected with said bridge bar and adjustable thereto by means of said holes, and an adjustable contact ring at the other end of said carbon rod connected to a conductor leading off the current. 65

3. An electric melting furnace consisting of a furnace body supported on trunnions turning on stands, and lined with insulating material, a carbon tube in said body projecting at both ends, two removable covers of 70 insulating material provided with central holes at both ends of said tube, a thin carbon rod guided in the holes of said two covers and projecting therefrom at both ends, whereby an annular space for the charge is 75 formed between said rod, the inside of said tube and said two covers; a contact ring adjustable on the tube at one end and connected with an inlet terminal, a similar contact ring adjustable on the tube at the other end 80 and conductively connected with a bridge bar provided with holes, an adjustable contact ring on the corresponding end of the carbon rod and conductively connected with said bridge bar and adjustable thereto by means of said holes, and an adjustable contact ring at the other end of said carbon rod connected to a conductor leading off the current. 85

In testimony whereof I hereto affix my 90 signature in the presence of two witnesses.

AUGUST VOELKER.

In presence of—

NIKOLAUS MEURER,
LOUIS VANDORY.
